SHIELDED COIL

Howard O. Berg, Chicago, Ill., assignor to Stewart-Warner Corporation, Chicago, Ill., a corporation of Virginia

Application April 10, 1943, Serial No. 482,528

5 Claims. (Cl. 250—16)

1

My invention relates to shielded coils and more particularly to permeability tuned intermediate frequency transformers.

An object of my invention is to provide a new and improved shielded coil which is of simple construction and more easily assembled than those heretofore known.

Another object of my invention is to provide a shielded coil which is cheaper to manufacture than the coils of the prior art.

Another object of my invention is to provide a shielded coil which is more efficient for all conditions of temperature and humidity than are the prior art coils.

Other objects and advantages will become apparent as the description proceeds.

In the drawings:

Fig. 1 is a longitudinal, sectional view through a shielded coil embodying a preferred form of my invention;

Fig. 2 is an end view of the coil of Fig. 1 looking in the direction of the arrows 2—2 of this figure;

Fig. 3 is an end view of the coil shown in Fig. 1 and is taken looking in the direction of the arrows 3—3 of Fig. 1;

Fig. 4 is a transverse, sectional view taken on the line 4—4 of Fig. 1;

Fig. 5 is a side elevation of the coil shown in Fig. 1;

Fig. 6 is a partial, transverse, sectional view showing a detail of construction and is taken on the line 6—6 of Fig. 3;

Fig. 7 is a longitudinal sectional view of the tube, electrical coils and condensers.

Fig. 8 is a wiring diagram showing the electrical connections for part of a typical radio circuit incorporating my invention.

In the drawings I have illustrated a thin walled tube 10 of Bakelite, ceramic or other suitable insulating and non-magnetic material on which the electrical coils 12 and 14 are wound. This tube is clamped between a pair of end plates 16 and 18 of Bakelite or other suitable insulating and non-magnetic material which serve to center the tube 10 and electrical coils 12 and 14 in spaced relation to a sleeve 20 preferably formed of iron dust and a suitable binder, such as powdered Bakelite.

The electrical coil 12 is provided with an iron dust core 22 mounted on a screw 24 threaded in the end plate 16. The screw 24 has a kerf 26 in its exposed end to facilitate adjustment of the core 22 lengthwise of the tube 10. The electrical coil 14 is similarly provided with an iron

dust core 28 mounted on a screw 30 threaded in the Bakelite end 18 and provided with an external kerf 32 to facilitate adjustment of the core 28 lengthwise of the tube 10.

5 The sleeve 20 is enclosed in a tubular metal shield 34 having an in-turned end 36 which overlies the end plate 16, and in-turned fingers 40 which overlie the end plate 18 whereby the shield 34 secures and holds the several parts in assembled relationship. L-shaped terminals 42 are attached to the end plate 18 by rivets 44, or in any other suitable manner, and the leads for the electrical coils 12 and 14 are soldered to the inner ends of these rivets, as indicated in Fig. 1, 10 there being four terminals 42 and a separate electrical coil lead soldered or otherwise secured to the rivet for each terminal.

In Fig. 7 I have illustrated more clearly the arrangement of the electrical condensers on the tube 10. At one end of the tube 10 films 50 and 52 of copper or other suitable metal are sputtered or otherwise formed on the inside and outside of the tube. The film 50 extends around the end of the tube and a short distance down 20 the outside thereof to permit an electrical conductor to be soldered or otherwise attached to this film. A gap 54 is located between the adjacent ends of the films so that each film forms 25 one plate of a condenser and the tube constitutes one plate of a dielectric between these plates.

The other end of the tube 10 is similarly provided with inner and outer sputtered films 56 and 58, respectively, which form the plates of a second condenser. These condensers are connected in parallel with the electrical coils 12 and 14, as indicated in Fig. 8 of the drawings, and where the tube 10 is used, it is unnecessary to provide my shielded coil with outside condensers as is the usual practice.

40 This Fig. 8 shows part of a typical radio circuit embodying my shielded coil. In this figure the electrical coil 12 and condenser 50—52 are arranged in parallel and interposed between the plate 60 of a radio frequency tube 62 and the positive pole of a B battery or its equivalent. The coil 14 and condenser 56—58 are also in 45 parallel and are interposed between the grid 64 of a second radio frequency tube 66 and a grounded terminal indicated at 68.

50 In assembling my new and improved coil, I have found it most advantageous to form two sub-assemblies which are subsequently brought together to make the completed shielded coil. One such sub-assembly is formed by inserting 55 screw 24 in end plate 16 and adjusting the screw

to bring the core 22 to approximately the proper position. Thereafter sleeve 20 is affixed to end plate 16 by applying a suitable cement, such as Glyptal, between the contacting surfaces of these parts, whereupon the end plate 16, core 22 and sleeve 20 are inserted in shield 34 to form one sub-assembly.

The other sub-assembly is formed by inserting screw 30 into end plate 18, attaching tube 10 to end plate 18 by means of Glyptal, or other suitable cement, and attaching the leads for the electrical coils—or for the electrical coils and condensers, as the case may be—to the terminal rivets 44 to complete the second sub-assembly. This second sub-assembly is then inserted in the sleeve 20 and shield 34 and the fingers 40 of this shield are then bent over to the position shown in Fig. 1 to complete the entire assembly.

I have found that my new and improved shielded coil is particularly efficient under all conditions of temperature and humidity where the interior of the coil is sealed against atmosphere. This can be effective by placing Glyptal or other cement between the engaging surfaces of the end plates and sleeve and by placing cement around the screws 24 and 30 at the outer surfaces of the end plates 16 and 18. These screws should only be sealed after the final adjustment of the cores 22 and 28 has been completed.

While I have described my invention as being particularly adapted for intermediate frequency transformers, my invention is not limited to such use and shielded coils embodying my invention may be used for other purposes. My invention is not limited to the particular details shown and described, but may assume numerous other forms and includes all variations and modifications falling within the scope of the appended claims.

I claim:

1. A shielded coil of the class described, comprising a non-magnetic and insulating tube having an inner and an outer metallic film at each end thereof, each inner film and its adjacent outer film forming a separate electrical condenser, electrical coils wound on said tube on the uncoated portion thereof, an iron dust core for each of said coils, said cores being movable lengthwise of said tube, an iron dust sleeve enclosing said coils and tube, end plates maintaining said tube and sleeve in spaced co-axial relationship, and a metal shield surrounding said sleeve and having portions overlying said end plates.

2. A shielded coil of the class described, comprising a dielectric tube having an inner and an outer copper film at each end thereof, each inner film and its adjacent outer film forming a separate electrical condenser, electrical coils wound on said tube on the uncoated portion thereof, a core for each of said coils, said cores being movable lengthwise of said tube, a magnetic sleeve enclosing said coils and tube, end plates maintaining said tube and sleeve in spaced co-axial relationship, and a metal shield surrounding said sleeve.

3. A shielded coil of the class described, comprising an insulating and non-magnetic tube having an inner and an outer metallic film at each end thereof, each inner film and its adjacent outer film forming a separate electrical condenser, an electrical coil wound on said tube on the uncoated portion thereof, an iron dust core for said coil, said core being movable lengthwise of said tube, an iron dust sleeve enclosing said coil and tube, means maintaining said tube and sleeve in spaced co-axial relationship, and a metal shield surrounding said sleeve and having portions overlying said end plates.

4. A shielded coil of the class described, comprising an insulating and non-magnetic tube having an inner and an outer metallic film at each end thereof, each inner film and its adjacent outer film forming a separate electrical condenser, electrical coils wound on said tube on the uncoated portion thereof, an iron dust core for each of said coils, an iron dust sleeve enclosing said coils and tube, end plates maintaining said tube and sleeve in spaced co-axial relationship, and a metal shield surrounding said sleeve and having portions overlying said end plates.

5. A shielded coil of the class described, comprising a ceramic tube having an inner and an outer metallic film at each end thereof, each inner film and its adjacent outer film forming a separate electrical condenser, electrical coils wound on said tube on the uncoated portion thereof, an iron dust core for each of said coils, said cores being movable lengthwise of said tube, an iron dust sleeve enclosing said coils and tube, end plates sealing the ends of said sleeve, a metal shield surrounding said sleeve and having portions overlying said end plates, and terminals for said coils and condensers attached to an end plate.

HOWARD O. BERG.
